UNITED STATES PATENT OFFICE.

SAMUEL W. EVANS, JR., OF PHILADELPHIA, PENNSYLVANIA.

UMBRELLA OR PARASOL RUNNER.

SPECIFICATION forming part of Letters Patent No. 259,676, dated June 20, 1882.

Application filed March 30, 1882. (No model.)

To all whom it may concern:

Be it known that I, SAMUEL W. EVANS, Jr., a citizen of the United States, residing in the city and county of Philadelphia, State of Pennsylvania, have invented a new and useful Improvement in Umbrella and Parasol Runners, which improvement is fully set forth in the following specification and accompanying drawings, in which—

10 Figure 1 is a side elevation of the umbrella-runner embodying my invention. Fig. 2 is a horizontal section thereof in line $\alpha\alpha$, Fig. 1.

Similar letters of reference indicate corresponding parts in the two figures.

15 My invention consists of an umbrella or parasol runner having a struck-up bead surrounding the slot, the edge of which is set out, whereby the runner is strengthened, and said edge does not project beyond either the inner 20 or outer surface of the runner, so that it does not cut the hand from without or rub the stick from within.

25 Referring to the drawings, A represents the runner of an umbrella or parasol, having a vertical slot, a , for the spring-catch, which is attached to the stick, as usual. The metal around the wall of said slot a is raised or stamped or struck up outwardly, forming a bead, B, which thus circumscribes said slot, 30 and the edge of the slot is slightly depressed, as at b , so as to set or project in a line within the circle described by the inner face of the runner and the larger circle described by the outer face of the runner with its raised edge.

35 It will be seen that the edge of the slot is

neither salient from within or without. It sets out from the stick, and thus avoids rubbing or scratching the same. It sets in from the outer surface of the runner, and thus obviates presenting itself to the thumb or fingers in 40 operating the spring-catch, and avoids cutting the thumb or fingers, or gloves, when worn. On the contrary, the raised bead provides a round and smooth surface throughout the entire length of the wall of the slot, thus overcoming the objection or remedying the defects in runners as heretofore constructed. Furthermore, the bead or rib crimps the metal of the runner and re-enforces the slot, and consequently increases the strength of the runner. 50

I am aware that it is not new to strengthen the slot of a runner by turning the metal outwardly on itself, this, however, leaving exposed edges, which are rough and liable to cut and tear the hand or glove in operating 55 the runner. Such construction I do not claim; but,

Having fully described my invention, what I do claim as new, and desire to secure by Letters Patent, is—

60 The runner having a struck-up bead surrounding the slot, the edge of which is set out, whereby the runner is strengthened, and said edge does not project beyond either the inner or outer surface of the runner, substantially as 65 and for the purpose set forth.

S. W. EVANS, JR.
